UNITED STATES PATENT OFFICE

121,608

DESIGN FOR A HOSE COUPLING

George K. Bedur, Akron, Ohio, assignor to The
B. F. Goodrich Company, New York, N. Y., a
corporation of New York

Application May 1, 1940, Serial No. 92,069

Term of patent 14 years

To all whom it may concern:

Be it known that I, George K. Bedur, a citizen of the United States, residing at Akron, in the county of Summit and State of Ohio, have invented a new, original, and ornamental Design for a Hose Coupling, of which the following is a specification, reference being had to the accompanying drawing, forming a part thereof, of which:

Fig. 1 is a perspective view of a hose coupling showing my new design.

Fig. 2 is a side elevational view thereof.

Both sides of the coupling are substantially like the side shown.

I claim:

The ornamental design for a hose coupling or the like, as shown and described.

GEORGE K. BEDUR.
